Specification for Design.

Patented July 12, 1921.

Application filed September 28, 1920. Serial No. 413,408. Term of patent 3½ years.

To all whom it may concern:

Be it known that I, MEYER L. ROBBINS, a citizen of the United States, residing in the city, county, and State of New York, have invented a new, original, and ornamental Design for a Ring or like Article, of which the following is a specification, reference being had to the accompanying drawing, forming a part hereof, in which the figure shown is a top plan view of a ring embodying my design.

One of the features of my design resides in the formation of the portion of the ring surrounding the emblematic portion, which formation corresponds in the outline to substantially the shape of the emblematic portion.

I claim:—

The ornamental design for a ring or like article, as shown and described.
